UNITED STATES PATENT OFFICE.

CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

971,955.

Specification of Letters Patent.

Patented Oct. 4, 1910.

Application filed May 31, 1910. Serial No. 564,227.

To all whom it may concern:

Be it known that I, CLIO B. YAW, citizen of the United States, and resident of Arlington, in the county of Hudson and State of 5 New Jersey, have invented certain new and useful Improvements in Type-Writing Machines, of which the following is a specification.

My invention relates to typewriting machines and more particularly to tabulating mechanism.

In tabulating mechanism heretofore employed it has been customary to use column stops adjustable along a column stop bar 10 to different positions corresponding to each index on the carriage scale or for each letter space position of the carriage in its line of travel. In the use of such column stops considerable time was required to set or adjust 15 them when a change from one character of work to another was made and the work involved in determining where to set the stops was somewhat troublesome.

One of the main objects of the present 20 invention is to overcome these difficulties and to provide comparatively simple and efficient mechanism for quickly determining the position of arrest of the carriage by the tabulator mechanism and for readily setting 25 the tabulator mechanism accordingly.

To the above and other ends which will hereinafter appear, my invention consists in the features of construction, arrangements of parts and combinations of devices to be 30 hereinafter described and particularly pointed out in the appended claims.

In the accompanying drawings, wherein like reference characters indicate corresponding parts in the various views, Figure 35 1 is a fragmentary side elevation with parts in section of one form of typewriting machine embodying my invention, only a sufficient number of parts of the machine being shown as is necessary to an understanding 40 of the invention. Fig. 2 is an enlarged detail fragmentary plan view of the column stops, the resetting mechanism therefor, and some of the associated parts. Fig. 3 is an enlarged detail perspective view of the 45 resetting cam or wiper. Fig. 4 is a detail vertical sectional view of the resetting mechanism, the section being taken on the line $x-x$ of Fig. 2 and looking in the direction of the arrow at said line. The parts in this 50 view are shown in normal position. Fig. 5

is a view corresponding to Fig. 4 but showing the resetting wiper in its projected or operative position.

I have shown my invention in the present instance embodied in a No. 11 Remington 60 typewriting machine which contains a denominational tabulator. It should be understood, however, that the character of the machine and of the tabulating mechanism employed is immaterial so far as my 65 present invention is concerned.

My invention has the same general objects in view, and may be considered in the nature of an improvement upon the constructions disclosed in the applications of Victor Albert Emanuel Sivertsen and Jans Christian Nielsen, filed April 8th, 1909, Serial No. 488,675 and George F. Ballou, Serial No. 541,995, filed February 10th, 1910, the present invention being directed more particularly 70 to the mechanism for resetting the column stops.

The frame of the machine comprises a base 1, corner posts 2 and a top plate 3. A carriage 4 is provided with grooved rails 5 which receive anti-friction balls or rollers 6, the latter being likewise received in fixed grooved guide rails 7, to support the carriage in its movement over the top plate 80 from side to side of the machine. The carriage carries the usual cylindrical platen 8 against the front face of which upwardly and rearwardly moving type bars 9 are adapted to strike. The front bar of the carriage is provided with the usual carriage 85 scale with which a pointer 10 co-operates, the pointer being secured by a screw 11 to the forward fixed carriage rail. Projecting rearwardly from the carriage are arms 12 which are fixed to the carriage by screws 13 90 and have secured thereto at their rear ends a column stop bar 14; screws 15 connecting the column stop bar to said arms. The column stop bar is provided with teeth 16 on the upper and lower sides thereof, forming 95 interdental spaces 16^a between the teeth. Bifurcated, plate-like column stops 17 straddle the column stop bar and are received and adapted to slide fore and aft 100 of the machine in the interdental spaces 16^a 105 between the teeth on the stop bar. The rear portion which connects the arms of each stop 17 constitutes the contact portion with which the co-operative tabulator stop or stops are adapted to engage. Each column 110

stop 17 is provided with an upwardly extending projection 18 formed with a vertical face with which a flat sheet metal bar 19 is adapted to coöperate to limit the rearward sliding movement of the column stops on the column stop bar. The bar 19 may be detachably fixed at its ends to the column stop bar so that a removal of the bar 19 affords a detachment of the column stops from the column stop bar when desired. The engagement of each bifurcated column stop with the walls of the interdental spaces 16^a is such as to afford sufficient friction to maintain each of the stops in the position to which it may be moved on the column stop bar. In other words, when a rearward movement of one of the column stops in its interdental spaces to operative position is effected it will be held in such position by frictional engagement with the column stop bar and when a stop is moved forward to inoperative position, it will likewise be held in such position by the frictional engagement with the column stop bar. So far as my present invention is concerned, it is immaterial how the column stops are constructed and how they are mounted for movement into and out of operative position. The construction shown in the present instance is somewhat similar to that disclosed in the application of George H. Smith, Serial No. 533,717, filed December 17, 1909, except that in the present instance the bar 19 is maintained fixed against movement on the column stop bar.

The column stops 17, when they are projected rearwardly to operative position are adapted to coöperate with tabulator or denominational stops 20 when the latter are projected forwardly to operative position by their key controlled mechanism. In the present instance I have shown a form of denominational tabulator such as that employed in the No. 11 Remington machine, though it should be understood that for the purpose of my present invention any desired form of tabulator mechanism may be employed to coöperate with the column stops. As shown in the present instance the denominational stops 20 constitute parts of upwardly extending denominational stop levers 21, pivoted at 22 to a tabulator frame 23. The frame 23 is secured by screws 24 and 25 to the frame of the machine so that the tabulator frame is rigidly connected with the main frame of the machine and, so far as the present invention is concerned, may be considered as a part of said main frame. The lower ends of the denominational stop levers are connected to push links 26 which in turn are connected to depending arms of angular actuating levers 27 pivoted on a rod 28 secured to the base of the machine. The forwardly extending arms of these angular levers are operatively

connected to key stems 29 guided in openings in guide plates 30 and 31. Restoring springs 32 are each connected at one end to the guide plate 31 and at the opposite end to the depending arm of one of the angular levers 27. A depression of one of the denominational tubulator keys 29^a is effective to project the associated denominational stop 20 forwardly into the path of those of the column stops 17 which have been moved to operative position. The carriage is at the same time released by the usual mechanism (not shown), such, for instance, as that employed in the No. 11 Remington machine.

In order to select or project any desired column stop to operative position I have provided selecting means which is coöperative with the column stops individually to move any desired one of them at a time to operative position, the particular stop which may be projected to operative position depending on the position of the carriage in its line of travel. Thus I have provided an actuating arm, finger or selecting device 33 formed as an upwardly extending crank arm 90 which projects from a hub secured to a rock shaft 34 mounted to turn in bearings in a bracket 35 detachably secured to the top plate of the machine. From an inspection of Fig. 2 it will be seen that the arm 33 is positioned so as to bring the free end portion thereof just to the right of the left-hand or decimal stop of the series of denominational stops. This arm is situated forwardly of the column stop bar 14, and forwardly of the column stops carried thereby, and at each letter space movement of the carriage, under control of the usual escapement mechanism (not shown), a column stop is brought into register with the contact portion of the setting or actuating arm 33; it being understood that there are preferably as many column stops as there are letter space movements of the carriage during a complete run or travel thereof. The width of the contact portion of the arm 33 is such as to enable the arm to co-act with each individual column stop without contacting with an adjacent column stop. As the arm 33 moves rearwardly one of the column stops is moved from its foremost position rearwardly to operative position, as indicated by the rearwardly projected stops in Fig. 2. The column stops thus projected to operative position are retained against accidental displacement from the operative position by the frictional engagement between the column stops and the column stop bar on which they are supported. The device 33 may be manually actuated in any suitable manner. In the present instance the rock shaft 34 has a hub secured thereto and from this hub extends a rearwardly projecting crank arm 36 to which is connected a downwardly extending link 37 130

bent as indicated at 38 to clear the top plate of the machine at the rear edge thereof. The lower end of the link 37 is connected to a key lever 39 fulcrumed on a plate 40 5 and provided with a restoring spring 41. This key lever preferably extends to the keyboard of the machine where it is provided with a selecting key 42 by which the rock shaft and the actuating device 33 may 10 be moved, to project the selected column stop to operative position.

In order to quickly restore all of the column stops to inoperative position, or to move them forwardly on the column stop 15 bar, I have provided a resetting device, wiper or cam designated as a whole by the reference numeral 43 and which is shown in detail in Fig. 3. This cam is provided with inclined faces 44 on the right and left-hand 20 sides thereof. The member 43 is in the nature of a slide and is mounted in a bearing formed in a casting 45 secured by screws 46 to the tabulator frame 23 which, as hereinbefore pointed out, may, for the purpose of 25 the present invention, be regarded as a part of the frame of the machine. The resetting device 43 is adapted to slide in its bearing in a horizontal plane and in the same general direction as the column stops in their movements to and from operative position and to 30 co-act with the projected column stops when the resetting device is in its operative position as indicated by dotted lines in Fig. 2. A depending pin 47 is received at its upper 35 threaded end in a tapped opening in the slide or device 43. The pin 47 is connected to one end of a contractile spring 48, the opposite end of which is connected to a pin 49 projecting from the bottom of the casting 40 45. From an inspection of Fig. 3 it will be seen that the member 43 has a cut-out portion 50, the forward end wall of which is formed as an inclined face or cam 51. A rod or slide or actuating device 52 is adapted 45 to move vertically or in a direction at substantially right angles to the plane of movement of the slide 43. The member 52 is supported and guided in its sliding movement within a bearing formed in the casting 50 45. The upper end of the slide 52 is provided with a finger key 53 detachably connected to the slide by a threaded connection 54. A coiled expansion spring 55 surrounds the member 52 and is received in a 55 recess 56 formed in the casting. The upper end of this spring bears against the hub of the finger piece or key 53, whereas the lower end of the spring bears against the bottom wall of the recess 56, thus tending normally 60 to maintain the member 52 in the elevated position shown in Fig. 4. The upward movement of the member 52 is limited by a cam head 57 formed on the lower end of said member and of larger diameter than 65 the bearing opening in which the member 52

is received. The cam head 57 is received in the cut-out or recessed portion 50 of the member 43 and an inclined face 58 on the cam head matches and is adapted to co-operate with the inclined face 51 on the 70 member 43. The parts are normally in the position shown in Fig. 4. A depression of the finger piece 53 against the pressure of the spring 55 is effective to cam the member 43 forwardly, as represented in Fig. 5 and 75 as represented in dotted line in Fig. 2, by the co-operation of the cam face 58 with the inclined face 51.

From an inspection of Fig. 5 it will be observed that there is a dwell 59 at the end of 80 the inclined face 58, and that this dwell is brought into co-operation with the corner or edge 60 on the member 43 when the finger piece 53 is fully depressed as represented in Fig. 5; the dwell 59 being in the nature of a 85 vertically disposed contact face with which the edge 60 cooperates to resist and positively prevent any rearward movement of the cam or member 43 until the finger piece 53 is released. By the releasing pressure 90 on the finger piece 53 the slide 52 will be carried upwardly, thus carrying the dwell out of engagement with the edge 60 and bringing the inclined face 58 into co-operation with the inclined face 51. As the upward 95 movement of the member 52 continues, the pressure of the spring 48 is effective to move the member 43 rearwardly to the inoperative position shown in Fig. 4, where it is no longer in the path of the projected column 100 stop.

It will be understood that a depression of the finger piece 53 projects the cam 43 to the dotted line position in Fig. 2 and that at this time a movement of the carriage is effective 105 to bring the different projected column stops successively into contact with the cam 43 and that the cam will force the projected column stops forwardly to inoperative position. If the movement of the carriage be 110 from right to left, then the right-hand face of the cam will co-act with the projected column stops, whereas if the movement of the carriage be from left to right, the left-hand face of the cam 43 will be effective to move the projected column stops forwardly to inoperative position. It will also be understood that any tendency to displace the cam from its projected position by the co-operation therewith of the projected column 115 stops, during the resetting movement of said stops is resisted by the engagement of the edge 60 with the dwell 59 on the member 52, so as to prevent the cam 43 from being displaced from its operative position till such time as pressure is released on the key 53. Moreover, it will be observed that by moving the cam 43 to and from operative position in the general direction of the movement 120 of the column stops to and from op- 125

- erative position, there can be no blocking of the cam in its movement to the projected or operative position. Thus, if any of the projected column stops should be opposite the 5 cam 43, when it is moved from the full to the dotted line position in Fig. 2, then the actuation of the cam 43 will merely result in moving such projected column stops forwardly without blocking the cam in its 10 movement to operative position, and as soon as a movement of the carriage is effected such stops will be moved farther forwardly if they have not been completely reset by the forward movement of the cam.
- 15 From the foregoing description it will be understood that in order to "clear" all of the projected column stops, it is merely necessary to depress the key 53 and effect a complete travel of the carriage from one 20 side of the machine to the other in either direction, which will result in a movement of all of the operative column stops forwardly to inoperative position.

In assembling the different members of 25 the resetting mechanism it may be assumed that the pin 47 is disconnected from the slide 43 and that the finger piece 53 is disconnected from the member 52. The cam 43 is then moved into a position corresponding substantially to that shown in Fig. 5 where the recess or opening 50 in the slide 43 is in a position to register with the cam head 57. The stem of the slide 52 is then moved upwardly through an opening 61 in 30 the casting 45 and through the opening 50 in the slide 43, the upper end portion of the member 52 being received in its bearing opening. The spring 55 is then placed in position and the finger piece 53 screwed in 35 place on the upper end of the member 52, thus preventing a disconnection of the members 52 and 43 from the casting in which they are received and adapted to slide. The pin 47 may then be screwed into position in 40 a tapped opening in the slide 43, and the spring 48 connected at one end to the pin 47 and at the opposite end to the pin 49. By disconnecting the finger piece 53 and the pin 47 the slides 52 and 43 may be with- 45 drawn by first removing the member 52 downwardly through the openings 50 and 61.

In the use of the device it may be assumed, 50 for instance, that a letter or invoice is to be written in which the vertical rows of names or items and amounts are to appear; which items and amounts in different lines are to be placed exactly under each other, and the carriage is moved to the position where the first letter of the first name or item is to be at 55 received. This will be assumed to be at "20", which is indicated by the pointer 10 on the carriage scale. The selecting key 29^a is then depressed and this effects a rearward movement of the finger, arm, projecting or 60 selecting device 33 and effects a rearward

movement of the particular column stop 17 which is opposite the contact portion of the selecting finger or device. Said column stop is thereby moved to operative position where it is retained against accidental displacement 70 by its frictional engagement with the column stop bar. Thereafter, during the tabulating operation, the projected column stop will always coöperate with the decimal stop at the same point, "20", in the travel of the carriage, where the carriage was arrested to select the column stop, and in the desired position where the first name or item to be written is to be started. If the operator desires to set the next column stop to write, for instance, an amount in the same line, so that the decimal point will be at say "50" on the carriage scale, it is only necessary to press down the selecting key 42 when the carriage is moved to a position where the decimal 80 point may be written in a position which corresponds to "50" on the carriage scale. This projects the column stop at "50", to arrest the carriage at such position when the decimal key is depressed. If in the next and 90 subsequent lines a name or item and an amount are to be written exactly under the first ones, no further setting of the stops is required and only those column stops are effective which have been moved to operative position by the actuation of the selecting key 29^a in the manner described. When the tabulator is to be set for a different character of work, requiring the use of different column stops, those formerly in use may be 100 "cleared", or moved to inoperative position by simply depressing the key 53, thereby moving the cam 43 to operative position in the manner hereinbefore described, and moving the carriage in the direction of its travel 105 while the cam is maintained in operative position. New column stops may then be individually and successively selected and set in the manner hereinbefore pointed out.

In accordance with the present invention 110 I prefer to employ a stop for each index on the carriage scale, or for each letter space position of the carriage, or at any rate for each index on the carriage scale, where ordinarily such stops might be employed and to provide 115 means whereby each of said stops can be thrown into and out of operative position, although, as hereinbefore indicated, the means for effecting this result may be varied at will, my invention being directed more 120 particularly to the resetting means for resetting the projected stops.

Various changes may be made without departing from the spirit and scope of my invention. 125

What I claim as new and desire to secure by Letters Patent, is:—

1. In a typewriting machine and tabulating mechanism, the combination of a carriage; a series of column stops; means for 130

projecting said stops individually to operative position, said means including means whereby the column stop which may be projected depends on the position of the carriage in its travel; a key controlled co-operative stop; and resetting means carried by the frame of the machine for moving the projected column stops to inoperative position, the movement of said resetting means being toward and away from said column stops in the same general direction that the said stops move in as they are projected to and moved from operative position.

2. In a typewriting machine and tabulating mechanism, the combination of a carriage; a series of column stops carried by the carriage; means carried by the frame of the machine for projecting said column-stops separately to operative position; a co-operative stop carried by the frame of the machine; key controlled means for projecting said co-operative stop into the path of the projected column stop or stops; and resetting means carried by the frame of the machine for moving the projected column stops back to inoperative position, the movement of said resetting means being toward and away from said column stops in the same general direction that the said stops move in as they are projected to and moved from operative position.

3. In a typewriting machine and tabulating mechanism, the combination of a carriage; a series of column stops situated a letter space distance apart and mounted for individual movement into and out of operative position and for maintenance indefinitely in either of such positions; key actuated means for moving any desired individual column stop to operative position; a co-operative stop; key controlled means for moving said co-operative stop to a position where it will co-operate only with the column stop or stops which are in the co-operative position; and resetting means carried by the frame of the machine for moving the projected column stops back to inoperative position, the movement of said resetting means being toward and away from said column stops in the same general direction that the said stops move in as they are projected to and moved from operative position.

4. In a typewriting machine and tabulating mechanism, the combination of a carriage; a series of stops; means for projecting said stops to operative position, said means including means whereby the stop which may be projected depends on the position of the carriage in its travel; a co-operative stop; and means independent of said projecting means for resetting said first mentioned stops to inoperative position, said resetting means including a part on the frame of the machine, and means for moving said part into and out of co-operative rela-

tion with said first mentioned stops, such movement of said part being in the same general direction as the movement of said first mentioned stops into and out of operative position.

5. In a typewriting machine and tabulating mechanism, the combination of a carriage; a series of stops; means for projecting said stops to operative position, said means including means whereby the stop which may be projected depends on the position of the carriage in its travel; a co-operative stop; and resetting means independent of said projecting means for resetting said first mentioned stops to inoperative position, said resetting means comprising a wiper, and means for moving said wiper into and out of the path of said first mentioned stops so that when the wiper is in operative position it will co-act successively with said first mentioned stops to move them back to inoperative position, the movement of said wiper into and out of operative position being in the same general direction as said stops in their movements into and out of operative position.

6. In a typewriting machine and tabulating mechanism, the combination of a carriage; a series of stops; means for projecting said stops to operative position, said means including means whereby the stop which may be projected depends on the position of the carriage in its travel; a co-operative stop; and resetting means independent of said projecting means for resetting said first mentioned stops to inoperative position, said resetting means comprising a cam, means for moving said cam into and out of operative relation with said first mentioned stops, the movement of said cam into and out of operative position being in the same general direction as the stops of said series in their movements into and out of operative position, and automatically acting means for locking said cam against the action of the series of stops when the cam is in co-operative relation therewith.

7. In a typewriting machine and tabulating mechanism, the combination of a carriage; a series of column stops carried by the carriage; means carried by the frame of the machine for projecting said column stops separately to operative position; a co-operative stop carried by the frame of the machine; key controlled means for projecting said co-operative stop into the path of the projected column stop or stops; and resetting means independent of the column stop projecting means for resetting all of the projected column stops to inoperative position, said resetting means comprising a wiper carried by the frame of the machine, means for rendering said wiper operative or inoperative on said column stops, the movement of said wiper into and out of operative

- position being in the same general direction as the said column stops in their movements into and out of operative position, and automatically acting means for locking said 5 wiper against the action of the column stops when the wiper is in the operative position.
8. In a typewriting machine and tabulating mechanism, the combination of a carriage; a series of column stops situated a 10 letter space distance apart and mounted for individual movement into and out of operative position and for maintenance indefinitely in either of such positions; key actuated means for moving any desired individual 15 column stop to operative position; a co-operative stop; key controlled means for moving said co-operative stop to a position where it will co-operate only with column stop or stops which are in the operative position; and resetting means independent of 20 said column stop moving means for resetting all of the operative column stops to inoperative position, said resetting means comprising a device operative successively 25 on the said column stops during the travel of the carriage, the movement of said device into and out of operative position being in the same general direction as the column stops in their movements into and out of 30 operative position.
9. In a typewriting machine and tabulating mechanism, the combination of a carriage; a series of column stops situated a letter space distance apart and mounted for 35 individual movement into and out of operative position and for maintenance indefinitely in either of such positions; key actuated means for moving any desired column stop individually to operative position; a co-operative stop; key controlled means for 40 moving said co-operative stop to a position where it will co-operate only with column stop or stops which are in the operative position; and resetting means independent of 45 said column stop moving means for resetting all of the operative column stops to inoperative position, said resetting means comprising a device operative successively on the said column stops during the travel of 50 the carriage, the movement of said device into and out of operative position being in the same general direction as the column stops in their movements into and out of operative position, said resetting means also 55 including automatically acting means co-operative with said device to lock it against return movement under the action of the column stops thereon.
10. In a typewriting machine and tabulating mechanism, the combination of a carriage; a series of column stops situated a letter space distance apart and mounted for 60 individual movement into and out of operative position and for maintenance indefinitely in either of such positions; key actuated means for moving any desired individual column stop to operative position; a co-operative stop; key controlled means for moving said co-operative stop to a position where it will co-operate only with column stop or stops which are in the operative position; and resetting means independent of 65 said column stop moving means for resetting all of the operative column stops to inoperative position, said resetting means comprising a cam operative successively on said column stops during the travel of the carriage, and means for moving said cam into and out of co-operative relation with said column stops, the movement of the said 70 cam into and out of co-operative relation with the column stops being in the same general direction as the column stops in their movements into and out of operative position, said resetting means also comprising means for locking the cam against return movement under the action of the column stops thereon.
11. In a typewriting machine and tabulating mechanism, the combination of a carriage; a series of column stops, one for each letter space movement of the carriage, said column stops being mounted for individual movement into and out of operative position; a selector co-operative with all of said 90 column stops individually, the particular column stop with which the selector is adapted to coact depending on the position of the carriage along its line of travel; a key actuated stop co-operative with said 95 column stop; a wiper operative successively on the column stops during the travel of the carriage to reset the column stops to inoperative position, the movement of the wiper into and out of operative position being in 100 the same general direction as the column stops in their movements into and out of operative position; and means for locking said wiper against return movement under 105 the action of the column stops on the wiper.
12. In a typewriting machine and tabulating mechanism, the combination of a carriage; a series of tabulator stops movable into and out of operative position and adapted to remain in either of said positions; key actuated selecting means for moving said 110 stops to operative position; a co-operative tabulator stop; and resetting means for moving said first mentioned stops to inoperative position, said resetting means comprising a restoring or resetting device cooperative with said first mentioned stops, said 115 first mentioned stops and restoring or resetting device being carried one by the frame of the machine and the other by the carriage, and the movement of said restoring device into and out of co-operative relation with the tabulator stops of the series being in the 120

same general direction as said stops in their movements into and out of operative position.

13. In a typewriting machine and tabulating mechanism, the combination of a carriage; a series of tabulator stops movable into and out of operative position and adapted to remain in either of said positions; key actuated selecting means for moving said stops to operative position; a coöperative tabulator stop; and resetting means for moving said first mentioned stop to inoperative position, said resetting means comprising a spring restored cam movable into and out of coöperative relation with said first mentioned stops, the cam when in coöperative relation effecting a successive resetting of the stops during the travel of the carriage, and the movement of said cam into and out of coöperative relation with the first mentioned stops being in the same general direction as said stops in their movements into and out of operative position, said resetting means also comprising an automatically operating lock for locking said cam against return movement by the action of the first mentioned stops thereon.

14. In a typewriting machine and tabulating mechanism, the combination of a carriage; a plurality of tabulator stops carried by the carriage and movable into and out of operative position and adapted to remain in either of said positions; a coöperative key actuated tabulating stop carried by the frame of the machine; and resetting means carried by the frame of the machine for moving said first mentioned stops to inoperative position, said resetting means comprising a member movable to resetting position in the same general direction as said plurality of tabulator stops in their movements to inoperative position.

15. In a typewriting machine and tabulating mechanism, the combination of a carriage; a plurality of tabulator stops carried by the carriage and movable into and out of operative position and adapted to remain in either of said positions; a coöperative key actuated tabulator stop carried by the frame of the machine; and resetting means carried by the frame of the machine for moving said first mentioned stops to inoperative position, said resetting means comprising a cam movably mounted on the frame of the machine into and out of the path of said first mentioned stops which have been moved to operative position so that during the travel of the carriage said operative stops will be cammed back to inoperative position; the movement of the cam into the path of the tabulator stops which have been projected into the operative position being in the same general direction as said stops in their movements to inoperative position, said resetting means also comprising a spring for moving

the cam back to inoperative position and locking means for locking the cam against return movement by the projected tabulator stops which coöperate therewith.

16. In a typewriting machine and tabulating mechanism, the combination of a carriage; a series of tabulator stops movable into and out of operative position; and means for resetting said stops, said resetting means comprising a resetting cam coöperative with said stops to move them to inoperative position, the cam and stops being carried one by the carriage and the other by the frame of the machine and the movement of the cam into coöperative relation with the stops being in the general direction of the movement of the stops to inoperative position.

17. In a typewriting machine and tabulating mechanism, the combination of a carriage; a series of tabulator stops movable into and out of operative position; and means for resetting said stops, said resetting means comprising a resetting cam coöperative with said stops to move them to inoperative position by a relative movement between said stops and carriage effected by the travel of the carriage, and means for moving said cam to operative position, said moving means comprising a finger piece and a controlling cam between said finger piece and said resetting cam.

18. In a typewriting machine and tabulating mechanism, the combination of a carriage; a series of tabulator stops movable into and out of operative position; and means for resetting said stops, said resetting means comprising a resetting cam coöperative with said stops to move them to inoperative position by a relative movement between said stops and carriage effected by the travel of the carriage, and means for moving said cam to operative position, said moving means comprising a finger piece and a controlling cam between said finger piece and said resetting cam, said controlling cam having a dwell which resists the movement of the resetting cam from operative or resetting position.

19. In a typewriting machine and tabulating mechanism, the combination of a carriage; a series of tabulator stops movable into and out of operative position; and means for resetting said stops, said resetting means comprising a resetting cam coöperative with said stops to move them to inoperative position by a relative movement between said stops and carriage effected by the travel of the carriage, and means for moving said cam to operative position, said moving means comprising a spring restored finger piece movable at substantially right angles to the direction of movement of said cam, and a controlling cam intermediate said finger piece and resetting cam.

20. In a typewriting machine and tabulating mechanism, the combination of a carriage; a series of tabulator stops movable into and out of operative position; and means for resetting said stops, said resetting means comprising a resetting cam coöperative with said stops to move them to inoperative position by a relative movement between said stops and carriage effected by the travel of the carriage, and means for moving said cam to operative position, said moving means comprising a spring restored finger piece movable at substantially right angles to the direction of movement of said

cam, and a controlling cam intermediate 15 said finger piece and resetting cam, said controlling cam having a dwell thereon which resists the return movement of the resetting cam under the action of the stops thereon.

Signed at the borough of Manhattan, city 20 of New York, in the county of New York, and State of New York, this 28th day of May, A. D. 1910.

CLJO B. YAW.
